UNITED STATES PATENT OFFICE.

WILLIAM H. BOYNTON, OF MORRIS PARK, NEW YORK, ASSIGNOR TO EMILY M. DUNTON, OF HOLLIS, NEW YORK.

CAR-TRUCK.

SPECIFICATION forming part of Letters Patent No. 562,212, dated June 16, 1896.

Application filed February 15, 1896. Serial No. 579,429. (No model.)

To all whom it may concern:

Be it known that I, WILLIAM H. BOYNTON, of Morris Park, Queens county, New York, have invented an Improved Car-Truck, of 5 which the following is a specification.

This invention relates to a car-truck for that class of railways in which the car engages a single rail on top and also a single rail at the bottom.

10 The car is propelled by means of the trolley system, and the object of the invention is more particularly to so construct the truck that it is properly counterbalanced and that it occupies a minimum amount of room in a lateral and also in a vertical direction.

15 In the accompanying drawings, Figure 1 is a horizontal section of my improved car-truck on line 1 1, Fig. 2; Fig. 2, a vertical longitudinal section on line 2 2, Fig. 1; and Fig. 3, a 20 vertical transverse section on line 3 3, Fig. 2.

The letter *a* represents a horizontal frame provided at its front and rear with boxes *a'*, in which are hung the axles *b'* of a pair of traction-wheels *b*. These wheels are placed 25 centrally within the frame and in line with one another, so as to engage the single track-rail *A*. Centrally between the axles *b'* there is hung in boxes *a²* of frame *a* the power-shaft *c*, that carries two electric motors *c'* of 30 ordinary or suitable construction.

These motors are preferably of the same weight and size and are secured to opposite ends of the shaft *c*, equidistant from its center, so that they counterbalance each other.

35 Upon the shaft *c* are furthermore mounted a pair of gear-wheels *c²*, each one of which is interposed between and engages a pair of wheels *b²*, mounted upon the axles *b'*. Thus it will be seen that the motion of the power-shaft is transmitted to the axles in order to 40 drive the same.

Upon the frame *a* is supported, by means

of springs *e'*, a second or upper frame *e*. This frame is provided with a central transverse beam *e²*, from which the king-bolt *e³* projects 45 upwardly. The car-body (not shown) engages this king-bolt in the ordinary manner, and is provided with means for engaging the upper or overhead guide-rail of the track.

The main advantages connected with my 50 truck are its compactness, both in a vertical and a lateral direction. Moreover, by mounting two motors upon the power-shaft, they serve to counterbalance each other, while at the same time they may be made so small as 55 not to necessitate an undue elevation of the king-bolt.

What I claim is—

1. A car-truck for a single-rail track, composed of a frame, a pair of axles hung therein 60 and carrying single traction-wheels, a power-shaft placed between the axles and gearing for connecting the power-shaft with the axles, substantially as specified.

2. A car-truck for a single-rail track, composed of a frame, a pair of axles hung therein and carrying single traction-wheels, a power-shaft placed between the axles, electric counterbalancing-motors secured to opposite ends of the shaft, and gearing for connecting the 70 shaft to the axles, substantially as specified.

3. A car-truck for a single-rail track, composed of a lower frame, a pair of axles hung therein and carrying single traction-wheels, a power-shaft placed between the axles and 75 intergeared therewith, a pair of motors secured to opposite ends of the shaft, an upper frame spring-supported upon the lower frame, and a king-bolt projecting upwardly from the upper frame, substantially as specified.

WILLIAM H. BOYNTON.
